UNITED STATES PATENT OFFICE

GEORGE MORRISON, OF POUGHKEEPSIE, NEW YORK

COIN CONTROLLED LOCKING MEANS FOR VENDING MACHINES

Original application filed August 14, 1930, Serial No. 475,169. Divided and this application filed June 10, 1931. Serial No. 543,323.

This invention relates to a vending machine and more particularly to a coin controlled locking device which by the insertion of the proper coin will release the vending mechanism and allow an article to be ejected for each coin which is inserted.

The object of the invention is to provide novel means whereby the vending mechanism is only released by the insertion of the proper coin, and all slugs, etc., of a similar diameter will be by-passed without operating the lock.

Another object of the invention is to provide means whereby several coins of the same 15 denomination which are equal in their combined value to a single coin of a larger denomination may with a slight change in the construction be used in place of the larger coin; such as five nickels may be used in the 20 place of one twenty-five cent piece.

The subject matter of this invention has been divided from my application for a patent on a vending machine, which was filed on August 14, 1930; Serial No. 475,169.

With these and other objects in view, my invention comprises certain novel construction and combination of parts as will herein-after be fully described and claimed, and illustrated in the accompanying drawing 30 which form a part hereof and in which like figures of reference refer to corresponding parts in all of the views.

In the drawing:—

Figure 1 is a partial side elevation of the 35 locking mechanism, shown with the outer casing removed to expose the working parts.

Figure 2 is a partial top plan view of the locking mechanism, shown partly in section.

Figure 3 is a similar view, but showing the 40 parts in another position.

Referring to the drawing:—

It is understood that this coin controlled locking mechanism may be employed with any suitable vending means, and is designed 45 to control the operation of the vending mechanism.

As the device is here shown, there is provided a mounting plate 10, within which is mounted the shaft 11 or the vending mechanism; this shaft 11 being provided with any

suitable escapement means, such as the wheel 12 and U-bar 13 pivoted as at 14 to the plate 10, and designed to be rocked by the reciprocation of the push rod 15 which is mounted in the bearings 16 attached to the plate 10 by the 55 screws 17; the tail of the U-bar 13 being engaged by a pin 18 secured in the bar or rod 15, and the tail being normally held in contact therewith by a spring 19 having one end secured to the bearing 16 and the other end to the 60 bar 13 as at 20.

That portion of the push rod 15 which is mounted in the bearings 16 is square in cross section to prevent its turning, while its forward end 21 is round and is slidably mounted 65 within a finger piece 22 which may be slidably mounted in the casing 23; said finger piece being tubular and provided with a spring 24 between the end of the rod 15 and the head 25; and for limiting the movement 70 of the finger piece 22 upon the rod 15, said rod is provided with a stop collar 26 secured thereon or forming a part thereof.

The rear part of the finger piece 22 is formed with a cutout portion 27, which when 75 said finger piece 22 is in an extended position, will register with the lower opening of a coin chute 28 which is formed between the plate 10 and a cover plate 29 secured thereto by the screws 30 and formed with a coin 80 race 31.

Located below the lower opening of the coin chute and also below the finger piece 22 is placed a coin stop 32, and between the lower 85 part of the coin chute 28 and the finger piece 22 is pivoted to the plate 10 as at 33, a detent 34 which is formed with a hooked end 35 which is normally adapted to engage a notch 36 which is formed in the upper face of the push rod 15; said detent or latch 34 90 is provided on its rear face with a pin or roller 37 and is held in a normally locked position by the spring 38 secured thereto and to a pin 39 in the plate 10.

In the operation of the device, a coin 40, 95 being inserted into the upper end of the coin chute 28 will drop down past the detent and enter the cutout portion 27 of the finger piece 22 and rest upon the coin stop 32 and in contact with the roller 37.

Now as the head 25 and finger piece 22 are pushed inward, the coin will be carried by the cutout 27 against the roller 37 and will lift the detent 34 and clear the hook 35 from the notch 36, allowing the push rod 15 to be moved inward by the end of the finger piece 22 contacting with the collar 26 as it is further moved inward; the pin 18 will move the tail of the U-bar 13 to release the escape wheel 12 and allow an article to be ejected from the vending machine.

A spring 41 is provided to retain the push bar 15 in a normally extended position.

After the coin 40 is carried inwardly by the further movement of the finger piece 22 after the same has contacted with the collar 26, the coin 40 will be carried past the coin stop 32 and will drop free from the cutout 27 into some suitable container.

Should it be desirable to operate the lock with a number of small coins, this is accomplished by placing the coin stop lower to allow several of the coins to pass through the cut out portion on the finger piece and stack up on the stop, the top coin being used as the wedge to operate the detent.

Having thus described my invention what I claim as new and desire to secure by Letters Patent, is—

A coin controlled lock for vending machines and in combination with a coin chute, of a push rod formed with a square portion and a round portion separated by a stop collar and having the squared portion slidably mounted in bearings, a finger piece formed with a bore and a head, and slidably mounted on the round portion of the push rod, a spring contained within the bore of the finger piece and in contact with the end of the round portion of the push rod to cushion its inward movement within said bore, the end of said finger piece adapted to abut the stop collar on the push rod upon compression of said spring, said finger piece being provided with a cut out portion to receive a coin, means to support a coin in the cut out portion, a detent for locking the push rod, the initial inward movement of the finger piece adapted to coat with a coin to release said detent from the push rod so that the further inward movement of the finger piece against the stop collar will impart movement to said push rod to operate the escapement mechanism.

In testimony whereof I affix my signature.

GEORGE MORRISON.
